SPRAY NOZZLE

Filed Dec. 6, 1926

BY

INVENTOR.

William H. Schneider

Louis O. French
ATTORNEY.

UNITED STATES PATENT OFFICE

WILLIAM H. SCHNEIDER, OF MILWAUKEE, WISCONSIN

SPRAY NOZZLE

Application filed December 6, 1926. Serial No. 152,927.

The invention relates to spray nozzles, and more particularly to spray nozzles for use in connection with carburetors although not necessarily limited thereto.

5 In the majority of carburetors in use today the flow of fuel to the mixing chamber or passage is controlled by a nozzle whose discharge orifice is regulated by a needle valve. While these needle valves are adjustable, they are generally set to effect a compromise to suit most running conditions of the motor and the result is that the fuel is not as efficiently sprayed as it should be, which results in imperfect mixing and hence 15 imperfect consumption. The object of this invention is to improve the nozzle structure of the carburetor by providing for a large area of fuel discharge and at the same time cause the fuel to be discharged in a fine 20 film into the mixing chamber for efficient mixture with the air on its way to the motor. More specifically, the invention consists in a nozzle formed by a coiled spring from whose closely spaced convolutions the fuel 25 enters or is sucked into the mixing chamber, preferably a Venturi passage.

The invention further consists in the several features hereinafter set forth and more particularly defined by claims at the conclusion hereof.

In the drawings Fig. 1 is a vertical sectional view through a carburetor embodying the invention;

35 Fig. 2 is a side elevation view of the nozzle shown in Fig. 1, parts being broken away;

Fig. 3 is a detail view of a part of the nozzle;

40 Fig. 4 is an enlarged bottom view of the rod shown in Fig. 3;

Fig. 5 is a view similar to Fig. 2, showing a modification;

Fig. 6 is a detail sectional view taken on the line 6—6 of Fig. 3.

45 In Fig. 1 I have shown a carburetor having a float chamber 7 into which the fuel is introduced in any suitable manner, the float 8 being operatively connected to the usual supply valve (not shown), said chamber being formed by a top casing 9 and a

shell 10 clamped to the tubular extension 11 of said casing by a nut 12.

The top casing 9 is provided with an air inlet passage 13, a Venturi mixing chamber or passage 14, and an outlet passage 15 having the butterfly throttle control valve 16 mounted therein, the extension 11 having a fuel passage 17 formed therein communicating by passages 18 with the interior of the float-chamber and conducting fuel to the nozzle.

The nozzle embodying the invention comprises, in each instance, a coil spring 19, preferably of square or rectangular cross section to present flat discharge surfaces, and means are provided for holding this spring in operative position at the upper end of the passage 17 and so as to extend into the mixing passage 14. While the spring may seat directly upon the upper end of the passage 17, I preferably, in each instance, secure an annular member 20 to its lower end by soldering it thereto and provide said member with a conical face 21 engageable with a concial seat 22 at the upper end of the passage 17.

For holding the spring 19 in operating position, I have shown, in Figs. 1 to 4, inclusive, a rod 23 having a threaded portion 24 engageable in the threaded opening 25 in the cap 26 secured to the casing 9 and provided with a fluted extension 27 of less diameter extending down through the spring and the opening in the member 20 and projecting into the upper end of the passage 17, said stem having grooves 28, best shown in Fig. 4.

The upper end of the spring 19 is secured, as by soldering, to an apertured or screenlike member 29 and a spring 30 is interposed between said disk and a shoulder 31 formed on the rod 23, said spring 30 being soldered to said parts. Thus the rod 23, spring 30, member 29, spring 19 and member 20 turn as a unit but when this unit is assembled in the carburetor, as shown in Fig. 1, turning of the rod in a clockwise direction will shorten the distance between the shoulder 31 and the member 20, the extension 17 being free to move lengthwise therein, with the result that the springs 19 and 30 are compressed until the coils of the spring 19 are brought so close-

ly together as to leave a very fine helical discharge opening therebetween, with the result that when the fuel is drawn by the suction of the air through the space between the coils it will be discharged therefrom in a thin film that will readily mix with the air passing through the Venturi passage 14. As the springs 19 and 30 balance each other, the disk or member 29 is free to move in the mixing passage, and for any initial setting of the nozzle unit an increase of air supply through a speeding up of the motor will cause an upward movement of the disk 29 with the result that the spring 30 is compressed somewhat and the spring 19 is permitted to elongate to some extent, thereby increasing the fuel discharge opening between the convolutions of the spring, and a decrease in suction will again cause the member 29 to move back to its initial position and thus cut down the effective nozzle discharge opening. Thus, the discharge area of the nozzle may be varied under varying demands of the motor.

In order, however, to simplify the construction, I may omit the automatic nozzle area regulating feature by omitting the member 29 and spring 30, and such a construction is shown in Fig. 5, wherein the upper end of the spring 19 is soldered direct to a shoulder 32 of a rod 33 having a threaded portion 34 which is designed to engage the threaded opening 25 in the same manner as the rod 23, said rod having a fluted extension 35 extending down through the spring and projecting into the upper end of the passage 17 when the nozzle is in assembled position in the carburetor, and when so assembled the spring 19 of the structure shown in Fig. 5 occupies the same position as the similar spring 19 of the unit shown in Fig. 1.

Assuming then that the nozzle shown in Fig. 5 is mounted in the Venturi passage 14, it will be noted that as the air flows up through said passage, under engine suction, fuel from the passage 17 will be drawn up through the grooves in the fluted extension into the interior of the spring and will then pass through the very narrow but long helical passage formed between the convolutions of the spring 19 and be discharged therefrom into the air in said passage, and since the adjustment of the rod 34 in the proper direction serves to decrease the length of the spring the space between the convolutions may be made very fine so that a filmlike discharge is assured and hence the fuel mixes readily with the air. Furthermore, as the total length of discharge opening is relatively large, efficient mixtures are formed under varying motor-operating conditions since on a decrease of velocity of air through the passage 14 less of the discharge will be effective for active fuel discharge than at higher speeds. In order, however, where conditions require it, to vary the nozzle area with vary-

ing speeds, I have provided the first-described construction.

I desire it to be understood that this invention is not to be limited to any specific form or arrangement of parts except in so far as such limitations are specified in the claims.

What I claim as my invention is:

1. In a carburetor, the combination with the mixing passage, of a fuel nozzle comprising a coiled resilient member for delivering fuel to the mixing chamber, said member having closely spaced convolutions, and separate means for supplying air to said mixing passage.

2. In a carburetor, the combination with the mixing passage, of a fuel nozzle comprising a coiled spring for delivering fuel to the mixing chamber, and means for adjusting said spring to space its convolutions for efficient fuel distribution therebetween, and separate means for supplying air to said mixing passage.

3. In a carburetor, the combination with the Venturi mixing passage, of a coil spring positioned in said passage and having its interior communicating with the fuel supply and its coil closely spaced to form a fuel discharge nozzle, and separate means for supplying air to said Venturi passage.

4. In a carburetor, the combination with the casing, the Venturi mixing passage, and the fuel supply conduit to said passage, of a spring having a seat member seated on the upper end of said conduit, a rod associated with said spring and adjustably mounted on said casing to hold said spring in operative fuel nozzle-forming position in said mixing passage, and separate means for supplying air to said mixing passage.

5. In a carburetor, the combination with a mixing passage, of a coil spring positioned in said passage and having its interior communicating with the fuel supply and its coils closely spaced to form a fuel discharge nozzle, means responsive to pressure changes in said chamber for varying the effective length of said spring to vary its nozzle discharge area, and separate means for supplying air to said mixing passage.

6. In a carburetor, the combination with the mixing passage, of a coil spring positioned in said passage and having its interior communicating with the fuel supply and its coils closely spaced to form a fuel discharge nozzle, means including a shiftable disk responsive to pressure changes in said chamber for varying the effective length of said spring to vary its nozzle discharge area, and separate means for supplying air to said mixing passage.

7. In a carburetor, the combination with the mixing passage, of a coil spring positioned in said passage, a fuel supply conduit communicating directly with the interior of said spring, and adjustable spring ten-

sioning means having a fluted extension fitting within said spring and extending into said conduit.

8. In a carburettor, the combination with the mixing passage, of a coil spring positioned in said passage and having its interior communicating directly with the fuel supply and its coils closely spaced to form a fuel discharge nozzle, a spring, a shiftable disk interposed between said nozzle spring and said last-named spring and responsive to pressure changes in said chamber for varying the effective length of said nozzle spring to vary its nozzle discharge area, and a centering member for said disk and springs.

9. In a carburettor, the combination with the mixing passage, of a coil spring positioned in said passage, a fuel supply conduit communicating directly with the interior of said spring, and adjustable spring-tensioning means having an extension fitting within said spring and provided with a fuel-distributing passage communicating with said conduit.

25 In testimony whereof, I affix my signature.
WILLIAM H. SCHNEIDER.
